UNITED STATES PATENT OFFICE.

WILLIAM R. STEARNS, OF MELROSE, AND G. WILTON LEWIS, OF MALDEN, MASSACHUSETTS, ASSIGNORS TO THE HIGHLAND SLATE MANUFACTURING COMPANY, OF PORTLAND, MAINE.

DESIGN FOR A GRAVE-STONE.

SPECIFICATION forming part of Design No. 18,198, dated March 20, 1888.

Application filed February 4, 1888. Serial No. 263,063. Term of patent 14 years.

To all whom it may concern:

Be it known that we, WILLIAM R. STEARNS, of Melrose, and G. WILTON LEWIS, of Malden, both in the county of Middlesex and State of Massachusetts, have invented and produced a new and original Design for a Head-Stone or Foot-Stone, of which the following, taken in connection with the accompanying drawing, is a specification.

10 This design relates to grave-stones for the graves of deceased soldiers.

The drawing shows in front elevation a portion of a grave-stone having our design thereon.

The design consists of a pair of crossed laurel-sprays inclosing space for any suitable inscription, the representation of an anchor, and an ornamental scroll shown composed of straight and curved lines and inclosing space for an inscription. As shown, the crossed laurel-sprays 15 and the anchor occupy the upper field of the design, while the scroll occupies the lower field.

Designs somewhat similar to that above described constitute the subject of an application filed by us October 25, 1887, No. 253,376, and two other applications of even date herewith, 25 respectively numbered 263,061 and 263,062.

We claim—

The design for a grave-stone herein shown and described, the same consisting of a pair of crossed laurel-sprays, the representation of an anchor, and an ornamental scroll.

In testimony whereof we have signed our names to this specification, in the presence of two subscribing witnesses, on this 2d day of February, A. D. 1888.

WM. R. STEARNS.
G. WILTON LEWIS.

Witnesses:

A. H. SPENCER,
GEORGE S. LITTLEFIELD.
